UNITED STATES PATENT OFFICE.

FRANK R. WATSON, OF BALTIMORE, MARYLAND.

STOVE-COVER.

1,273,700.

Specification of Letters Patent. Patented July 23, 1918.

Application filed March 5, 1918. Serial No. 220,443.

To all whom it may concern:

Be it known that I, FRANK R. WATSON, a citizen of the United States, residing at Baltimore city, State of Maryland, have invented certain new and useful Improvements in Stove-Covers, of which the following is a specification.

This invention relates to improvements in lids for closing the openings in stove tops, and its object is to provide the lid with an opening for insertion of the lifter whereby the lid is removed from the stove top, said lid opening being provided with a novel and improved closure as will be described in detail hereinafter.

In order that the invention may be better understood, reference is had to the accompanying drawing forming a part of this specification, and in said drawing—

20 Figure 1 is a perspective view of the lid; Fig. 2 is a bottom plan view of a fragment of the lid, and Figs. 3 and 4 are sections on the line 3—3 and 4—4, respectively of Fig. 2.

25 Referring specifically to the drawing, 5 denotes a stove lid having a rabbetted edge to fit in the opening of the stove top, the latter not being shown as the manner in which the lid is used is well known. In order that 30 a lifting tool may be readily applied to the lid for the purpose of removing the same from the stove top, or for replacing the same, the lid is provided with an opening 6 extending completely through the same 35 from the top to the bottom. The lifter is shown dotted at 7. This lid opening is provided with a closure 8 which, when the lifter is not applied, completely closes the opening, and comes flush with the top of the lid. One end of the closure is counter- 40 weighted, as shown at 9, so that the closure has a normal tendency to swing to closing position and stay closed. The thickened portion of the closure forming its counter- 45 weighted end is at the bottom, so that the top of the lid is left perfectly smooth.

On the under side of the closure 9 are outstanding ears 10 which are opposite ears 11 depending from the bottom of the lid, and 50 through these matching ears is passed a pivot pin 12, whereby the closure is pivotally connected to the lid, so that it may be swung open and closed.

The forward edge of the closure 9 is beveled and the contiguous edge of the opening 6 is correspondingly beveled, as shown in Fig. 3. These bevels are in a direction to permit the forward portion of the closure to swing downward only. The rear edge of the closure, where it is counterweighted, is 55 also beveled, with the contiguous edge of the opening 6 correspondingly beveled, as shown in Fig. 3. These bevels are in a direction to permit the rear portion of the closure to swing upward only. The sides of 60 the closure, as shown in Fig. 4, ahead of the pivotal connection, are beveled in the same manner as the forward edge of the closure. By beveling the edges of the closure in the manner described, it seats normally flush 65 with the top of the lid 5, and swings back to this position when the lifter 7 is removed.

The lifter 7 is applied to the lid 5 by inserting its outer end into the opening 6 to come beneath the same as shown in Fig. 3, 70 this being done by pressing the lifter down on the forward end of the closure 9 to swing said end down as shown in dotted lines in Fig. 3, the opposite, or rear end swinging upward. When the lifter is removed, the 75 closure swings back to its normal closing position. It will be noted in Figs. 1 and 3, that the lifter has side lugs 13 adjacent to its working end, which lugs engage the top 80 of the lid to serve as a fulcrum for the lifter. 85 Where the lifter is not provided with these side lugs, some provision must be made to obtain a fulcrum support for the lifter. This can be done by forming the ears 11 with out- 90 standing stop lugs 14, located beneath the closure 9 in the path thereof, and thus serv- 95 ing to limit its downward swing, as shown in Fig. 3. The closure can swing open only far enough for the insertion of the lifter, a further swing being prevented by the lugs 14. Hence, the closure serves as a fulcrum support or abutment for the lifter, to prevent the same from slipping from holding position as the lid is being lifted.

The device is very simple and inexpensive, it is adapted for all types or styles of stove lid lifters, and it therefore effectively serves the purpose for which it is designed.

I claim:

A stove lid having a lifter opening ex- 105 tending therethrough, depending ears on

the bottom of the lid on opposite sides of the opening, a swinging closure seating in the opening and having its rear end weighted, ears on the closure intermediate the ends thereof and matching the ears on the lid, a pivot pin passing through the matching ears, and lugs extending inward from the ears on the lid and engageable by the for-

ward portion of the closure to limit the swing thereof. 10

In testimony whereof I affix my signature in the presence of two witnesses.

FRANK R. WATSON.
